CLAIM

The ornamental design for a laser marking instrument for construction as shown and described.

DESCRIPTION

FIG. 1 is a top, front and right side perspective of a laser marking instrument for construction showing our new design;

FIG. 2 is a bottom, back and left side perspective thereof; FIG. 3 is a bottom, front and left side perspective view thereof;

FIG. 4 is a front view thereof;

FIG. 5 is a back view thereof;

FIG. 6 is a top plan view thereof;

FIG. 7 is a bottom plan view thereof;

FIG. 8 is a right side view thereof; and,

FIG. 9 is a left side view thereof.

In the drawings, the broken lines depict portions of the laser marking instrument for construction that form no part of the claimed design.
